CLAIM

The ornamental design for a playing apparatus for playground, substantially as shown and described.

DESCRIPTION

FIG. 1 is a perspective view of the playing apparatus for playground;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

The dash lines shown in these figures are for illustrative purposes only and form no part of the claimed design.

The broken lines shown in the figures form no part of the claimed design.

1 Claim, 8 Drawing Sheets
